HUNTER'S KNIFE

Heino F. Bohlmann, 3000 S. Bellaire St., Denver, Colo.

Filed Dec. 26, 1958, Ser. No. 53,908

Term of patent 14 years

(Cl. D22—3)

Figure 1 is a side elevational view of a hunter's knife showing my new design;

Figure 2 is a bottom edge view thereof;

Figure 3 is a transverse sectional view taken substantially on the line 3—3 of Figure 1; and

Figure 4 is a transverse sectional view taken substantially on the line 4—4 of Figure 1.

The design is characterized by a transversely double-beveled elongated blade having a bevel line running centrally thereof, having a blunt top edge, having a crescent-shape hook at the end remote from the handle beveled contiguously with the blade and terminating in a pointed tip, and having along the bottom edge adjacent the handle a notch provided with a top edge sloping upwardly

toward the bevel line and an end edge sloping downwardly toward the handle, all as shown.

I claim:

The ornamental design for a hunter's knife, substantially as shown and described.
